GANG FORM FOR CASTING BLOCKS

Kenneth C. Wissinger, Altoona, Pa.

Application June 26, 1947, Serial No. 757,151

12 Claims. (Cl. 25—121)

1

This invention relates to gang forms for casting a plurality of similar concrete or like building blocks having intermediate openings and end grooves which are vertically disposed and registered when the blocks are laid in horizontal courses with mortar between the blocks of successive courses.

An important object of the present invention is to provide a form of the above kind including vertical longitudinal plates provided with transverse openings and end recesses, and highly elastic inflatable cores adapted to be extended through said openings and recesses and to be distended between said longitudinal plates to a cross-sectional size larger than said openings and recesses for the production of blocks whose openings and grooves are of relatively small area at the ends thereof and of greater area between said ends, thereby producing blocks which have maximum mortar service areas, but which are light in weight and embody only enough concrete or like material to afford the necessary strength.

Another object of the invention is to provide a form of the above kind in which certain of the cores and upper and lower separator strips for the longitudinal plates coact with the latter and with each other to provide the form with cells in which the blocks are cast.

A further object is to provide a form of the above kind which is durable, light in weight, and easy to assemble, and which may be bodily lifted, upon removal of the cores, without being partially dismantled, for casting a next layer of blocks on a previously cast layer thereof, the longitudinal plates and lower separator strips extending below the casting spaces so as to extend between the sides and ends of the blocks in said previously cast layer and prevent the concrete or the like from flowing therebetween when the next layer is cast.

Another object is to provide novel means for securing the upper end separator strips in place and for utilizing hoist lines for lifting the form, and novel means for securing the lower separator strips in place.

The exact nature of the present invention, as well as more specific objects and features thereof, will become apparent from the following description when considered in connection with the accompanying drawings, in which:

Figure 1 is a side elevational view of a form embodying the present invention and illustrated as set for casting blocks on blocks previously cast in the same form.

Figure 2 is a top plan view of the form shown in Figure 1.

2

Figure 3 is a longitudinal section of the construction as shown in Figure 1, taken on the plane of line 3—3 of Figure 2.

Figure 4 is an end elevation looking toward the left of Figure 1.

Figure 5 is a transverse section taken on line 5—5 of Figure 1.

Figure 6 is a transverse section through the form, taken on line 6—6 of Figure 2.

Figure 7 is an enlarged fragmentary vertical section taken on line 7—7 of Figure 2.

Figure 8 is a vertical transverse section taken on line 8—8 of Figure 1 with the blocks omitted.

Figure 9 is a central longitudinal section through one of the blocks taken on line 9—9 of Figure 1.

Referring in detail to the drawings, the present form includes vertically disposed longitudinal form plates 10 and 11, vertical upper transverse separator strips 12, vertical lower end separator strips 12' and vertical lower intermediate separator strips 13. Each upper separator strip 12 is arranged in vertical alignment with a lower separator strip 12' or 13. The upper separator strips 12 are provided with a plurality of spaced vertical slots 14 extending from their lower edges upwardly toward their upper edges and spaced apart a distance determined by the dimensions of the blocks to be cast. The lower transverse separator strips 12' and 13 are provided with similar slots 15 which extend from their upper edges downwardly. By registering the longitudinal plates 10 and 11 with the slots 14 and 15, the plates and separator strips may be assembled with the aligned strips 12 and 12' and 12 and 13 in vertically spaced relation to form cubical cells in which individual blocks may be cast.

The longitudinal plates 10 and 11 are provided with registered end recesses 16 and registered openings 17 for reception of cores 18 which are threaded transversely through said recesses 16 and openings 17. Certain of the cores 18 extend between the vertically aligned end separator strips 12 and 12' and between the vertically aligned intermediate separator strips 12 and 13.

Such cores comprise elastic inflatable tubes provided with inflation valves 19 and adapted to be inflated so as to be distended between the longitudinal plates 10 and 11 to close the spaces between the aligned upper and lower separator strips and to have a cross-sectional size between said longitudinal plates larger than the openings 17 and recesses 16. The inner longitudinal edges of the separator strips are curved as at 20 to permit this at the top and bottom of each core,

but the lateral distension of the cores may be limited or controlled by reinforcing the sides of said cores with imbedded inelastic fabric. By providing elastic inflatable cores which are so distended, blocks 21 may be produced whose end grooves 22 and openings 23 are of relatively small area at the ends as indicated at 24 in Figure 9, and are of greater area between such ends as indicated at 25. This provides blocks which have maximum mortar surface areas at the opposite faces 26, but which are light in weight and embody only enough concrete or like material to afford the necessary strength. In other words, the material is saved in a quantity corresponding to the increase in diameter and/or cross-sectional size of the recesses 22 and openings 23 between the ends 24. However, this does not unduly weaken the blocks and in no way reduces the mortar surface areas.

The lower separator strips 12' and 13 project below the longitudinal plates 10 and 11, and said longitudinal plates extend downwardly beyond the bottom of the casting spaces. Thus, upon upward stripping of the form to the position of Figures 1 and 3 to 5 inclusive, the downwardly extending edges of the plates 10 and 11 and lower separator strips 12' and 13 will embrace the previously cast blocks to support the form for casting a second layer of blocks and will extend between the adjacent side and end faces of the blocks in the first layer to prevent the concrete from flowing downwardly therebetween when poured in the form for casting said second layer. It will be noted that the inner faces of the cell walls formed by the longitudinal plates and separator strips are smooth and free of projections, so that the form may be bodily lifted to the new casting position without in any way dismantling said form and after removal of the cores only. Such removal of the cores may be readily and quickly effected by partially deflating them.

The longitudinal plates 10 and 11 are provided at their ends with upper and lower projecting tongues 27 and 28. Angle lifting bars 29 are disposed transversely of and beneath the upper tongues 27 so that depending flanges thereof aid in retaining the end cores 18 in place, and these lifting bars are provided with spaced eye members 30 for engagement by the hooks 31 of hoist lines 32, used in lifting the form to new casting positions. The lifting bars are disposed against the outer sides of the upper end separator strips 12', and clips 33 straddle the projections 27 at the outer sides of the end separator strips 12' to aid in holding them in place, said clips 33 having outturned lower ends engaged beneath the upper horizontal flanges of the lifting bars 29 as indicated by dotted lines in Figure 4 and shown by full lines in Figure 8. The lifting bars 29 have notches 34 in the free longitudinal edges of their horizontal flanges to permit passage of the clips 33 therethrough.

The lower end separator strips 12' are held in place by means of set-screws 37 threaded through depending nut members 38 fixed to the lower edges of the projections 28 on the ends of longitudinal plates 10. The nut members 38 are located outwardly of strips 12', and by threading the screws 37 inwardly, said strips 12' are held in proper position against outward pressure.

The intermediate separator strips 12 and 13 engage between pairs of spaced plates 39 bolted to the outer faces of the longitudinal plates 10 at opposite sides of the openings 17 vertically.

aligned with said separator strips 12 and 13. The adjacent vertical edges of plates 39 are spaced apart a distance equal to the thickness of the strips 12 and 13, and the bolts 40 fastening said plates 39 in place preferably have their heads countersunk in the plates 10 as shown clearly in Figure 7. In this way, lateral displacement of the strips 12 and 13 is prevented. The plates 39 are provided at the bottom of their adjacent vertical edges with outwardly projecting lugs 41, and the lower separator strips 13 are provided near their ends with openings 42 which receive wedges 43 that bear on the upper edges of lugs 41 and draw the strips 13 upwardly into place, as well as to firmly retain said strips 13 in place. By using the plates 39, the lugs 41 need not be welded directly to the longitudinal form plates 10, and said plates 39 effectively brace the strips 12 and 13 against lateral movement.

In use, the form may first be set up over wooden planks or any other suitable foundation, and then the cells of the form are filled with concrete or like material which is screeded flush with the top edges of the longitudinal form plates 10. At this time, the lower edge portions of form plates 10 and the lower separator strips 12' and 13 extend below the foundation members and therefore below the casting space of the form. When this first layer of blocks has set sufficiently to permit removal of the form, the cores 18 are partially deflated and removed, and the form proper is elevated to the position of Figures 1 and 3 to 5 inclusive, without removing any of the form plates or separator strips. When this is done, the form plates and lower separator strips project between the blocks in the layer just cast so as to support the form for casting a second layer and to fill the spaces between the adjacent blocks of the first layer to prevent concrete or the like from flowing between said blocks of the first layer when the second layer is cast. Lifting or elevation of the form is conveniently effected by means of the hoist lines 32 and hoisting or lifting bars 29. No time is lost in removing or replacing any of the separator strips or form plates when the form is lifted to the new casting position. Before the second or next layer of blocks is cast, the upper surfaces of the blocks in the previously cast layer are sprayed or otherwise coated with a suitable material which will prevent said next layer of blocks from adhering to the blocks of the previously cast layer. Such material may also serve the added function of waterproofing the surfaces of the blocks and/or giving such surfaces a special finish.

From the foregoing description, it is believed that the construction, manner of use and advantages of the present invention will be readily understood and appreciated by those skilled in the art. Modifications and changes in details of construction are contemplated, such as fall within the scope of the invention as claimed.

Having described the invention what is claimed as new is:

1. A gang form for casting a plurality of similar blocks having intermediate openings, comprising a plurality of more than two longitudinal form plates, transverse upper and lower separator strips for said longitudinal plates arranged in pairs with those of each pair in vertically aligned and spaced relation, means to removably secure the lower separator strips in place, said longitudinal plates having registered intermediate openings for reception of cores between adjacent

pairs of the separator strips and for reception of a core between the separator strips of each pair, and inflatable elastic cores extending through said openings.

2. A gang form for casting a plurality of similar blocks having end grooves and intermediate openings, comprising a plurality of more than two longitudinal form plates and transverse upper and lower separator strips for said longitudinal plates arranged in pairs with those of each pair in vertically aligned and spaced relation, means to removably secure the lower separator strips in place, said longitudinal plates having registered end recesses and intermediate openings for reception of cores, certain of said openings being located between the separator strips of each pair so that the latter separator strips will coat with cores placed in said certain openings and said recesses to provide the form with a plurality of cells and to form the end grooves in the blocks, and inflatable elastic cores extending through said openings and recesses.

3. The construction defined in claim 2, wherein in said cores are distended between adjacent longitudinal plates to a size larger than said openings and recesses to retain the cores in place and to produce blocks whose openings and grooves are of relatively small area at the ends thereof and of greater area between such ends.

4. The construction defined in claim 2, wherein in said cores are distended between adjacent longitudinal plates to a size larger than said openings and recesses to retain the cores in place and to produce blocks whose openings and grooves are of relatively small area at the ends thereof and of greater area between such ends, said separator strips having recessed edges adjacent the associated cores to permit such distension of the cores.

5. The construction defined in claim 2, wherein said longitudinal plates are provided at their ends with upper and lower projecting tongues, and angle lifting bars extending transversely of and beneath the upper tongues and provided with eye members adapted to be engaged by the hooks of hoisting lines used in lifting the form.

6. The construction defined in claim 2, wherein in said longitudinal plates are provided at their ends with upper and lower projecting tongues, and angle lifting bars extending transversely of and beneath the upper tongues and provided with eye members adapted to be engaged by the hooks of hoisting lines used in lifting the form, and substantially U-shaped clips engaged over the upper tongues at the outer sides of the upper end separator strips and engaged beneath the lifting bars to retain the upper end separator strips in place.

7. The construction defined in claim 2, wherein in said longitudinal plates are provided at their ends with upper and lower projecting tongues, and angle lifting bars extending transversely of and beneath the upper tongues and provided with eye members adapted to be engaged by the hooks of hoisting lines used in lifting the form, said lifting bars having depending flanges disposed at the outer sides of the end cores extended through the end recesses of the longitudinal plates for retaining said end cores in place.

8. The construction defined in claim 2, wherein

70

said longitudinal plates are provided with projecting upper and lower end tongues, depending nut members rigid with the lower projecting tongues, and set screws threaded through said nut members and impinging the lower end separator strips at the outer sides of the latter for retaining the same in place.

9. The construction defined in claim 2, wherein in the separator strips are provided with a plurality of spaced vertical slots to receive the edges of the longitudinal plates, spaced bracing plates secured to the outer faces of the longitudinal plates in spaced relation and receiving the intermediate ones of the upper and lower separator strips therebetween, said bracing plates having recesses in adjacent edges thereof for passage of the associated cores therebetween.

10. The construction defined in claim 2, wherein in the separator strips are provided with a plurality of spaced vertical slots to receive the edges of the longitudinal plates, spaced bracing plates secured to the outer faces of the longitudinal plates in spaced relation and receiving the intermediate ones of the upper and lower separator strips therebetween, said bracing plates having recesses in adjacent edges thereof for passage of the associated cores therebetween, outwardly projecting lugs on the bottom of the adjacent edges of said bracing plates, the intermediate lower separator strips having openings, and wedges passing through the last-named openings above the outwardly projecting lugs for securing said intermediate lower spacer strips in place.

11. The construction defined in claim 2, wherein in the lower separator strips depend below the longitudinal plates, whereby upon lifting the form the downwardly extending edges of the lower separator strips will extend between and close the spaces between the ends of adjacent ones of the blocks of a previously cast layer to prevent concrete from flowing between said blocks when casting a second layer of blocks upon the first layer thereof.

12. The construction defined in claim 2, wherein in the lower separator strips depend below the longitudinal plates, whereby upon lifting the form the downwardly extending edges of the lower separator strips will extend between and close the spaces between the ends of adjacent ones of the blocks of a previously cast layer to prevent concrete from flowing between said blocks when casting a second layer of blocks upon the first layer thereof, said form being bodily liftable without dismantling of the separator strips or longitudinal plates and upon removal of the cores.

KENNETH C. WISSINGER.
